UNITED STATES PATENT OFFICE.

GEORGE C. REITH, OF PHILADELPHIA, PENNSYLVANIA, ASSIGNOR, BY MESNE ASSIGNMENTS, TO NATIONAL SALES MACHINE COMPANY, OF WORCESTER, MASSACHUSETTS, A CORPORATION OF MASSACHUSETTS.

VENDING MACHINE AND THE LIKE.

1,421,831.

Specification of Letters Patent. Patented July 4, 1922.

Application filed December 14, 1917. Serial No. 207,035.

To all whom it may concern:

Be it known that I, GEORGE C. REITH, a citizen of the United States, residing at Philadelphia, in the county of Philadelphia and State of Pennsylvania, have invented 5 a new and useful Improvement in Vending Machines and the like, of which the following, together with the accompanying drawings, is a specification.

10 The objects of my present invention are to provide means for clearing the track of the coin as it enters the machine from any extraneous matter which would tend to clog the track and impede the passage of the coin; 15 also to provide means for interrupting the passage of pieces whose diameter is less than the normal diameter of the coin for which the machine is adapted.

These objects, among others, I accomplish 20 by the construction and arrangement of parts as hereinafter described and illustrated in the accompanying drawings, the novel features of my invention being pointed out in the annexed claims.

25 In the accompanying drawings,

Figure 1 represents a side elevation of an inclined coin chute through which a coin is conducted to the vending machine.

Figure 2 represents the lower or rear end 30 of the coin chute, having the movable parts in their normal position.

Figure 3 represents the lower or rear end 35 of the coin chute with the movable parts rocked into the position assumed in clearing the track or chute for the passage of a coin.

Figure 4 is a side elevation of the coin chute, a portion having been removed to disclose the mechanism for interposing a gate in the track of the coin.

40 Figure 5 is a detached perspective view of the gate whereby the passage of the coin through the chute is interrupted.

Figure 6 is a top view of the mechanism for interposing a gate in the track of the 45 coin.

Figure 7 is a side elevation of the coin chute, showing the side opposite that represented in Figure 1.

Figure 8 is a sectional view on the broken 50 line 8—8, Figure 1.

Figure 9 is a sectional view on the broken line 9—9, Figure 1.

Figure 10 is a sectional view on the broken line 10—10, Figure 1, showing the gate 18 in position to impede the coin in its passage through the chute, and 55

Figure 11 is a similar sectional view to Figure 10, showing the gate removed from the track of the coin.

Similar reference characters refer to similar parts in the different figures.

Referring to the accompanying drawings, 1 denotes the front portion of the framework of the machine to which a concave plate or escutcheon 2 is attached, provided 65 with a slot of suitable size to admit a coin therethrough into the inclined chute 3. The chute 3 consists of a plate 4 held in a substantially vertical plane and having at its lower edge a narrow flange 5 which forms 70 the track for a rolling coin in its passage through the chute. During the passage of the coin through the chute its upper edge is inclosed by a flange 6 upon a rocking frame 7. 75

The rocking frame 7 carries at its upper end a cam shaped projection 8, normally extending into the path of the coin as it is inserted through the slot 9 into the chute. The pressure exerted upon the coin to crowd 80 it past the cam shaped projection 8 serves to rock the frame 7 from the position shown in Figure 2 to that shown in Figure 3. The frame 7 carries at its lower end a flange 10 which works through a slot 11 in the plate 4. 85

The frame 7 is held in its normal position, as represented in Figure 2, by means of a spring 12 inserted between the plate 4 and the frame 7, the movement of the frame 7, as actuated by the spring 12, being limited 90 by the head of a screw 13 held in the plate 4 and extending through a slot in the frame 7. When the frame 7 is rocked by the passage of a coin past the cam shaped projection 8 from the position shown in Figure 2 to 95 that shown in Figure 3, the flange 10 is moved over the flange 5 which forms the track for the coin. Any extraneous material which may have been inserted through the slot 9 upon the track of the coin is pushed off by 100 the movement of the flange 10. As soon as the coin passes the cam shaped projection 8, the frame 7 is swung back to its normal position by the tension of the spring 12,

thereby withdrawing the flange 10 from over the flange 5 and freeing the track for the passage of the coin. The upper end of the frame 7 is pivoted to the frame work of the chute by a pintle 14, and the lower end of the frame 7 is pivoted by a pintle 15 to a bar 16 attached by a screw 17 to the lower end of the plate 4.

In order to impede the passage of a coin through the chute having a diameter less than the normal diameter of the coin required to operate the vending machine, I interpose in the path of a coin a swinging gate 18, pivoted by pintles 19, 19 to the plate 4, the gate 18 being shown in perspective view in Figure 5. The upper part of the gate 18 extends over the plate 4 and is provided with an incline 20 interposed in the path of the coin. The gate is also provided with a shoulder 21, in front of which the free end of a pivoted lever 22 rests upon the gate, forming a latch 23. The contact of the shoulder 21 with the latch 23 prevents the rearward swinging movement of the gate which is so suspended upon its pintles that gravity, when the latch is removed from the shoulder 21, will swing the gate in the direction of the arrow 24 and withdraw the gate from the path of the coin. The lever 22 is pivoted at 25 and it extends into the path of the coin, as shown in Figure 4. As the coin rolls beneath the lever 22, the latch 23 is raised to release the shoulder 21 and allow the gate 18 to swing by gravity to withdraw its free end from the path of the coin. As the coin passes the gate 18, it rolls beneath the incline 20, which positively rocks the gate 18 to throw its free end again into the path of the coin when it is locked by the latch 23. If the coin is of less than the required diameter, it will fail to lift the lever 22 as it passes beneath it and the gate 18 will remain in locked position, with its free end interposed into the path of the coin, as represented in Figure 2. The coin impeded by the gate 18 will be thrown off the flange 5 by the inclined side of the gate and fall into a receptacle prepared for rejected coins, not shown. The lifting of the lever 22 unlatches the swinging gate 18 and allows it to be withdrawn by gravity from the path of the coin. When the coin passes beneath the incline 20, it rocks the gate by a positive movement to bring its free end again into the path of the coin. If, for any reason, the coin should fail to restore the free end of the gate 18 to its locking position in the path of the coin, its restoration will be effected by the insertion of a succeeding coin into the chute. As a coin is pushed against the cam shaped projection 8, the frame 7 will be rocked and the gate 18 will be swung forward by the swinging movement of the flange 10 striking against the rear side of the gate. The flange 10 is

notched at 26 to allow the gate to swing back by gravity when the frame 7 is in its normal position.

I claim—

1. In an apparatus of the type specified, a coin chute having a track for the coin, a movable member normally positioned at one side of said track and movable transversely across the track for clearing the same, means whereby said member may be operated to clear said track by the insertion of a coin into said chute, a gate occupying normally an out-of-the-way position with relation to said track but movable to occupy an engaging position in the path of a coin moving over said track, and means for locking said gate in its engaging position whereby the gate may be released to occupy its out-of-the-way position by the approach to the gate of a coin of predetermined diameter, said movable member and gate being arranged whereby the gate may be moved into its engaging position by the operation of said movable member for clearing said track. 90

2. In an apparatus of the class described, a track for supporting a coin, a gate pivotally suspended above the track to swing by gravity out of the path of the coin, means for positively swinging the gate into the path of the coin by the movement of a coin over said track, and means for releasably maintaining the gate in the path of the coin whereby the gate may be released by a coin of predetermined diameter. 100

3. In an apparatus of the type specified, a track for a coin, a gate movable into a position transverse the track or into an out-of-the-way position with relation thereto, means for mounting the gate to assume normally an out-of-the-way position with relation to the track, means whereby the gate may be moved into a position transverse the track by a coin passing over said track, and means for releasably locking the gate when in position transverse the track whereby the gate may be released into its normal out-of-the-way position by a coin of predetermined diameter passing along said track. 110

4. In an apparatus of the type specified, a track for the coin, a gate movable into a position transverse the track or into an out-of-the-way position with relation thereto, means for mounting the gate to assume normally an out-of-the-way position with relation to the track, means arranged beyond said gate and actuated by a coin passing over said track for moving the gate into its engaging position transverse the track, and locking means for releasably maintaining the gate in such engaging position, said locking means being movable into a disengaging position releasing the gate by a coin of predetermined diameter passing along said track in front of said gate. 120 130

5. In an apparatus of the type specified, a coin chute having a bottom supporting plate for supporting the bottom edge of the coin and on which the coin runs, a plate for laterally supporting one side of the coin, a guide for the top edge of the coin, a gate movable through said side plate into an engaging position transverse the bottom plate and path of the coin or into a disengaging position 10 with relation thereto, means for mounting the gate to assume normally a disengaging position, means whereby the gate may be moved into its engaging position by a coin passing along said chute, and means for 15 maintaining the gate in its engaging position, said last-named means being releasable to release the gate into its disengaging position by a coin of predetermined diameter passing along said chute.
6. In an apparatus of the class described, 20 a track for supporting a coin, a gate movable by gravity out of the path of the coin, means for moving the gate positively into the path of a coin, and means for locking the gate in its position in the path of the coin, said 25 last-named means being releasable for releasing the gate by the approach to the gate of a coin of a predetermined diameter.

GEORGE C. REITH.
